Primary Examiner—Kay H. Chin

(22) Filed: **Nov. 22, 2000**

(57) CLAIM**(30) Foreign Application Priority Data**

The ornamental design for a screen holding device, as shown and described.

Jul. 14, 2000 (CH) 127068

DESCRIPTION

(51) LOC (7) Cl. **14-02**
(52) U.S. Cl. **D14/452**; D14/451
(58) Field of Search D14/448, 451,
D14/452; 248/917-924, 346.01, 346.02;
361/679-685; D6/449, 491, 445, 396, 512;
200/5 R, 5 A, 6 R, 6 A

FIG. 1 is a front perspective view of a first embodiment of a screen holding device showing our new design;
FIG. 2 is a first (left) side view of the first embodiment;
FIG. 3 is a second (right) side view of the first embodiment;
FIG. 4 is a front view of the first embodiment;
FIG. 5 is a rear view of the first embodiment;
FIG. 6 is a top view of the first embodiment; and,
FIG. 7 is a bottom view of the first embodiment.

UNITED STATES PATENT AND TRADEMARK OFFICE
CERTIFICATE OF CORRECTION

PATENT NO. : Des. 462,359 S
DATED : September 3, 2002
INVENTOR(S) : Alexander Scharer et al.

Page 1 of 1

It is certified that error appears in the above-identified patent and that said Letters Patent is hereby corrected as shown below:

Title page.

Item [30], **Foreign Application Priority Data**, please correct the priority date from "Jul. 14, 2000" to -- May 23, 2000 --.

Signed and Sealed this

Fourth Day of February, 2003

JAMES E. ROGAN
Director of the United States Patent and Trademark Office
